(57) **CLAIM**

The ornamental design for a “blended falx winglet” as shown and described.

DESCRIPTION

This application is related to commonly owned U.S. patent application Ser. No. 18/463,625 filed on Sep. 8, 2023.

FIG. 1 is a top perspective environmental view thereof;

FIG. 2 is a rear perspective view thereof;

FIG. 3 is top plan view thereof;

FIG. 4 is a bottom plan view thereof;

FIG. 5 is a rear elevation view thereof;

FIG. 6 is a front elevation view thereof;

FIG. 7 is a left side elevation view thereof;

FIG. 8 is a right side elevation view thereof; and,

FIG. 9 is a front perspective view thereof.

The broken lines in the drawing Figures denote structure that is in the environment of the claimed design which is not a part of the claimed design.
